UNITED STATES PATENT OFFICE.

LEWIS STEIDLE, OF MAUCH CHUNK, PENNSYLVANIA.

RAILROAD-TIE.

1,160,460.

Specification of Letters Patent.

Patented Nov. 16, 1915.

Application filed November 9, 1914. Serial No. 871,115.

To all whom it may concern:

Be it known that I, LEWIS STEIDLE, a citizen of the United States, residing at Mauch Chunk, in the county of Carbon and State 5 of Pennsylvania, have invented certain new and useful Improvements in Railroad-Ties, of which the following is a specification.

My invention relates to improvements in railroad ties, the object of the invention being to provide a tie which is composed largely of metal containing blocks of wood, and to which the rails are secured.

A further object is to provide a tie of the character stated which is of general box 15 form having openings at its center in its top and bottom for the reception of the ballast, so that the tie can be securely anchored in the roadbed and held against possibility of creeping in any direction.

20 A further object is to provide a metal tie in which wooden blocks, relatively small, can be utilized, and which is especially adapted for using sections of ties which are partially rotted or worn, and which would otherwise 25 be destroyed.

With these and other objects in view, the invention consists in certain novel features of construction and combinations and arrangements of parts as will be more fully 30 hereinafter described and pointed out in the claim.

In the accompanying drawings: Figure 1 is a top plan view illustrating my improved tie. Fig. 2 is a view in side elevation with 35 the central portion shown in longitudinal section to illustrate the openings in the top and bottom of the tie, and Fig. 3 is a fragmentary view on an enlarged scale in longitudinal vertical section on the line 3—3 of Fig. 1.

I represents my improved tie which is of metal and rectangular in cross section. The tie is made hollow throughout its length, and is open at both ends, so that blocks 2, preferably of wood, may be readily inserted into the tie from the ends thereof, and may be withdrawn from the tie whenever desired. To facilitate this withdrawal of the blocks, I provide slots 3 in the top 4 of the tie, and 50 an ordinary pick or other device may be forced into the wooden block when inserted through the slot 3, and then such instrument used to draw the block through the end of the tie.

55 The top 4 and the bottom 5 of the tie are

provided midway between the ends of the tie with relatively large openings 6 and 7 respectively, so that the ballast of the roadbed may be positioned in the tie through the openings 6 and 7, and securely anchor the tie to the roadbed, preventing any possibility of creeping in any direction.

The top 4 of the tie is provided with openings 8 exposing the blocks 2, and on these exposed portions of the blocks, the rails 9 are secured by spikes 20. The openings 8 are appreciably wider than the base portions of the rails, and the tie at both side edges is recessed as shown at 10 so that the rail may rest in a horizontal plane and lie upon the block. The ends of the recesses 10, adjacent the ends of the tie, form shoulders 11 against which the base flanges of the rails are positioned so as to prevent any spreading of the rails, and to further overcome any tendency of the rails to spread, I may locate braces 12 against the outer faces of the rails and secure such braces to the tie by spikes 13. The braces 12 have lugs 14 which bear against the walls of the opening 8, so that these lugs assist the spikes in holding the braces against movement. At the sides of the tie, adjacent the recesses 10, I provide reinforcing integral extensions 15. These extensions operate to receive the rails thereupon when the load is upon the rails, and sustain to a large degree, the pounding of the passing train.

In addition to the spikes above enumerated, I provide spikes 16 which are positioned through openings 17 in the top 4 of the tie, and driven into the blocks 2 so as to hold the blocks against possibility of movement. These spikes 16 are driven into the blocks when they are first positioned in the tie, and it is of course to be understood that before the blocks can be removed, all of the spikes must be first removed.

While I have illustrated single blocks in each end of the tie, it is to be understood that I do not limit myself in this particular, as I may employ any such number of blocks, and various other slight changes might be made in the general form and arrangement of parts described without departing from my invention, and hence I do not limit myself to the precise details set forth, but consider myself at liberty to make such changes and alterations as fairly fall within the spirit and scope of the appended claim.

Having thus described my invention, what I claim as new and desire to secure by Letters Patent is:

The combination with a hollow metal tie, 5 of blocks in both ends of the tie, said tie having openings in its top and recesses at its sides narrower than the openings, said tie having integral laterally projecting enlargements at its sides, wider than a railroad rail 10 and having rail receiving recesses in their

upper ends registering with said first-mentioned recesses, substantially as described.

In testimony whereof I have signed my name to this specification in the presence of two subscribing witnesses.

LEWIS STEIDLE.
